(57) CLAIM

The ornamental design for a garden lopper, as shown and described.

DESCRIPTION

FIG. 1 is a top right perspective view of a garden lopper showing our new design;

FIG. 2 is a right side view thereof;

FIG. 3 is a left side view thereof;

FIG. 4 is a top view thereof;

FIG. 5 is a bottom view thereof;

FIG. 6 is a front view thereof; and,

FIG. 7 is a rear view thereof.

The broken lines in the drawings are included for the purpose of illustrating portions of the garden lopper that form no part of the claimed design.
